UNITED STATES PATENT OFFICE.

SHERARD OSBORN COWPER-COLES, OF SUNBURY-ON-THAMES, ENGLAND.

CONTINUOUS AUTOMATIC PROCESS FOR THE PRODUCTION OF METAL SHEETS, WIRE, TUBES, CYLINDERS, AND OTHER ARTICLES.

Application filed October 2, 1922. Serial No. 591,784.

To all whom it may concern:

Be it known that I, SHERARD OSBORN COWPER-COLES, a subject of the King of Great Britain, residing at Rossal House, 5 Thames Street, Sunbury-on-Thames, Middlesex, England, have invented a Continuous Automatic Process for the Production of Metal Sheets, Wire, Tubes, Cylinders, and Other Articles, of which the following

10 is a specification.

My invention relates to the production of finished metal products such as sheets, wire, tubes, cylinders, and other articles which are usually rolled, drawn, spun, stamped or cast 15 and to a process of electro-depositing the desired metal or alloys, or combination of metals, on specially prepared mandrels or cathodes coated with lead or a film of sulphide or oxide, so that the deposited metal 20 can be readily removed by rolling, or in any other suitable manner, when it has attained the desired thickness or dimensions.

In previous patents I have described methods of rapidly electro-depositing metals 25 by revolving or reciprocating a cathode at a high rate of speed. I have found, however, that such a process possesses the disadvantage that the cathode, in spite of its rotation, carries around with it a film of electrolytic solution which has been largely denuded of its metal contents. This occurs 30 even if baffle-plates are employed.

The effect of this film, which for convenience is hereinafter referred to as the 35 cathodic film, is prejudicial not merely by reason of its poverty in metal but also from the fact that electrolytic action upon it results in the rapid evolution of gas bubbles immediately adjacent to the cathode surface 40 which tends to disintegrate the deposit and render the cathode surface rough and uneven.

The object of the present invention is to enable high current densities to be employed 45 and thus to increase the field of application of the process and to this end it consists in giving the cathode an oscillating or reciprocating motion of such rapidity that it will, either alone or in conjunction with a continuous or intermittent rotary motion, shake off or disperse the denuded cathodic film.

In suitable apparatus for making foil and sheet metal I employ an open ended cathode

cylinder in connection with driving rollers carried on a frame above the depositing vat 55 and capable of rotation at any desired speed, the rollers being so arranged as to allow the cylinder to be immersed in the solution to about three-quarters of its diameter. One roller is arranged inside the cylinder and 60 another roller opposite to it on the outside, pressure being applied to them by means of springs or weights to give the necessary friction to revolve the cathode cylinder, other rollers being provided as supports and 65 guides to keep the cylinder in position. Electric contact is made with the cathode cylinder by means of one or more of the rollers or a suitable rubbing contact. The carrying frame for the rollers and the 70 cathode cylinder is mounted so that it can be given a rapid oscillating or reciprocating motion, thus causing the cylinder to oscillate correspondingly in the electrolyte, and to throw off the cathodic film, thereby obviating 75 the injurious effects of any gas bubbles and permitting intimate contact or skin friction between the deposited metal and the solution and at the same time circulating the 80 solution, thus enabling a high current density to be employed whilst keeping the voltage at the minimum.

The importance of the rapid oscillating or reciprocating motion is as above stated that the cathodic film of electrolyte denuded of its 85 metal content, which would otherwise adhere to the cathode and result in the evolution of gas around the latter, is broken up, thus enabling a much higher current to be employed than has hitherto been possible. 90 The rapidity or frequency of the oscillating or reciprocating motion may vary, provided that it is at least sufficient to disintegrate the cathodic film, when depositing lead if a surface speed of 100 feet per minute is given 95 to the cathode, a current density of 100 amperes per square foot or more can be employed.

The required minimum speed of reciprocation of the cathode to disperse the denuded 100 cathodic film aforesaid in most cases can be ascertained by observing at what speed gas bubbles cease to appear on the cathode surface and where a speed of cathode has been 105 pre-determined it is only necessary, in operating the process, gradually to increase

the current until a point is reached where gas bubbles commence to appear. It will thus be clear that the current is too high and must be reduced until all signs of gas generation at the cathode surface cease.

The improved process enables metallic foils and sheet to be made continuously, and also wire by providing the cathode cylinder with a spiral or parallel V-shaped scratch or groove so as to form a weak line of cleavage in the deposit in the known manner. Or, tubes and cylindrical objects may be made by attaching to the cylinder, or an endless belt working on cylinders, suitable moulds or matrices which are given an oscillatory motion and at the same time made to travel through the solution at a predetermined speed so as to obtain the desired thickness of metal in one or more revolutions. Or, tubes may be formed upon mandrels carried directly upon the reciprocating frames.

To enable the invention to be fully understood, I will describe it by reference to the accompanying drawing, in which:—

Figure 1 is a plan of apparatus constructed in accordance with the invention for the electro-deposition of metallic foil.

Figure 2 is a vertical section of the apparatus on the line 2—2 of Figure 1, and

Figure 3 is a sectional view at right angles to Figure 2, with certain parts omitted.

a is the depositing vat and *b* the open ended cathode cylinder, *b*¹ is the anode in the form of a bar of semi-circular form supported in, but insulated from, the vat *a* and arranged with its inner surface in close proximity to the outer surface of the cylinder *b* and equi-distant therefrom.

c is the frame for supporting the cylinder *b* in the vat *a* through the medium of the supporting and guiding rollers *d*, *d*, the said frame comprising two side portions or cheeks *c*¹ tied together by cross-bars *c*² and *i*. The said rollers are mounted on spindles carried in bearings *d*¹ in the said frame and are arranged in contact with the inner peripheral surface of the said cylinder and provided with flanges for guiding purposes.

e, *f* are the driving rollers for the cathode cylinder *b*, the said rollers being arranged in contact with the inner and outer peripheral surfaces of the said cylinder and mounted upon spindles also carried in bearings *g* in the frame *c*. The said bearings are slidably mounted in guideways *g*¹ in the frame *c* and are pressed upon by springs *g*² to cause the rollers *e*, *f* to grip the cylinder *b* between them, the roller *e* being rotated by a sprocket-wheel *h* and chain *h*¹ from any suitable driving means to frictionally turn the said cylinder in the electrolyte in the vat *a*.

The frame *c* is supported by extensions on the rod *i* mounted in bearings *i*¹ and de-

signed to slide endwise therein, so that the said frame together with the cathode cylinder *b* can be reciprocated laterally with respect to the vat *a*. This reciprocating motion is shown as being imparted to the said frame by a shaft *j* through the medium of an eccentric *j*¹ and connecting rod *j*², but any other suitable means may be employed.

By effecting such reciprocation of the cathode cylinder *b* rapidly to insure the dispersal of the cathodic film within the electrolyte in the vat *a* I am enabled to employ a high current density for effecting the deposition on the cathode with a minimum voltage.

The cathode cylinder *b* is rotated at such a speed that the foil or sheet deposited thereon has acquired the desired thickness as it emerges from the electrolyte, the said foil or sheet being peeled off from the cylinder and passing between a pair of trimming rollers *k*, *k*¹ supported in bearings in the frame *c* and geared together as indicated at *k*² and driven from the shaft of the roller *c* by sprocket gear *k*³. *k*⁴ is a shoot for the trimmings from the trimming rollers *k*, *k*¹. From the said rollers the foil passes to, and is wound on, a roller *l* mounted in bearings in the frame *c* and upon which bears another roller *l*¹ carried in bearings in a lever frame *m* pivoted on a shaft *m*¹ also carried in bearings in the said frame, the said roller *l*¹ being rotated, to frictionally rotate the roller *l*, by sprocket gear from the said shaft *m*¹ which is itself rotated from any suitable driving source by sprocket gear *m*². *n* is a container and pad for applying the coating of stripping solution to the surface of the cathode cylinder before it passes below the surface of the electrolyte and *n*¹ is a container pad for washing such treated surface directly after the application of such stripping solution.

o is a brush for brushing the deposit on the cathode as it emerges from the electrolyte and *p* is a roller for squeegeeing the deposit after the brushing operation, the deposit then being washed by water from a tank *q*.

By providing the cylinders *b* with a spiral or parallel V-shaped scratch in the known manner the deposit can be unwound from the said cylinder in the form of wire.

Having now particularly described and ascertained the nature of my said invention and in what manner the same is to be performed, I declare that what I claim is:—

1. An electrolytic process for the production of metal sheets, wires, tubes, cylinders and other articles wherein the cathode has imparted to it an oscillating or reciprocating motion in the electrolyte of a rapidity or frequency sufficient to throw off or disperse the denuded cathodic film.

2. An electrolytic process for the produc-

tion of metal sheets, wires, tubes, cylinders and other articles wherein the cathode has imparted to it an oscillating or reciprocating motion and also a continuous or intermittent 5 rotary motion, in the electrolyte of a nature and frequency such as will throw off or disperse the denuded cathodic film, substantially as and for the purpose described.

3. Apparatus for carrying out the process 10 claimed in claim 2, comprising a cathode cylinder, a frame for supporting the same, means for rotating the cylinder in the electrolyte and means for oscillating or reciprocating the said frame and cylinder, substantially as described.

4. Apparatus for carrying out the process 15 claimed in claim 1 wherein the cathode is provided with one or more V-shaped scratches or grooves for the purpose set forth.

5. Apparatus as claimed in claim 3 wherein 20 the cathode cylinder is provided with a

spiral or parallel V-shaped scratch or groove for the purpose set forth.

6. The apparatus for the production of 25 metal sheets or wire, constructed, arranged and operating, substantially as hereinbefore described and illustrated in the accompanying drawings.

7. An electrolytic process for the production of metal sheets, wire, tubes, cylinders and other articles wherein the cathode has imparted to it an oscillation or reciprocating motion in the electrolyte of a rapidity or frequency at the rate of 100 to 125 reciprocations per minute.

8. An electrolytic process for the production of metal sheets, wire, tubes, cylinders and other articles wherein the cathode has imparted to it an oscillation or reciprocating motion in the electrolyte of a rapidity or frequency regulated to prevent the formation 40 of gas bubbles on the cathode surface.

SHERARD OSBORN COWPER-COLES.
